VIBRATOR

John G. Krenzke, La Porte, Ind., assignor to Donald M. Stevenson, Carrie S. Logan, Carolyn S. Rathjen, and Warren A. Stevenson, all of La Porte, Ind., doing business as Stevenson Mfg. Co.

Application January 8, 1940, Serial No. 312,951

6 Claims. (Cl. 128—33)

The vibrator of the present invention is designed for imparting vibrations of variable intensity to the human body for the purpose of stimulating the blood circulation, relieving nervous or muscular tension and fatigue, and for otherwise relieving bodily or mental disturbances or discomforts.

The vibrator is adapted to apply general vibration to the body as a whole or to localize the same mainly within given regions of the body, although in the form shown the device provides a platform upon which the user may stand or sit, so that the vibratory effects will be distributed in greater or less degree to all portions of the body, and may be regulated in intensity by controlling the motor speed at a rate which is most effective for any specific case in order to produce results that are pleasant and beneficial to the user.

20 Further objects and details will be apparent from the description of the invention in conjunction with the accompanying drawing, wherein—

25 Figure 1 is a perspective view of the vibrator as a whole in a form exemplifying the principles of the present invention;

Fig. 2 is a sectional elevation taken on line 2—2 of Fig. 1; and

30 Fig. 3 is a sectional elevation taken on line 3—3 of Fig. 2.

The vibrator as a whole is mounted within a box-like casing 10 of metal, comprising a base or floor 11, end walls 12, and front and rear walls 13. The casing is open at its top, and within the 35 casing are mounted a pair of standards 14 located near the end walls of the casing, each standard being of S-shaped formation, terminating at its lower end in an inturned floor flange 15 and at its upper end in an outwardly turned supporting flange 16, which flanges in conjunction 40 support a platform 17, which is elevated above the upper edges of the casing walls and terminates around its margin in a depending flange 18 which overlaps the margins of the casing.

45 The standards 14 are formed of relatively thin plates of metal having a considerable degree of resiliency, so that when subjected to the vibratory action presently to be described they will, through a minute range, oscillate back and forth in a direction transverse to the plane of the standards, so that a minute and very rapid four-way movement will be imparted to the platform upon which the user stands, sits or lies, in order 50 to receive the vibratory effect imparted by the

apparatus. The standards at their lower ends are attached to the floor of the casing by screws 19 entered through the inturned foot flanges 15 and held in place by nuts 20.

The attachment for the platform is afforded by screws 21 entered through the supporting flanges 16 each held in place by a nut 22, and in order to provide a cushion for the platform and reduce noise and friction, a bushing 23 with a neck 24 of rubber or the like is interposed between the platform and the flange 16, with the neck entered through an aperture in the flange and the parts held in place by a washer 24a and the nut 22. Likewise, for the purpose of cushioning the base of the casing, depending feet 25 are provided at each corner, which serve to support the casing in elevated relation to the floor or other supporting surface.

It will be noted that the standards 14 (Fig. 3) are relatively broad in proportion to their height, 20 and that they extend almost the full width of the casing, so that adequate provision will be made for supporting the weight of the person upon the platform without, however, stiffening the standards to a degree which would impair their 25 efficiency in imparting vibratory movements to the platform. The standards are connected by a horizontal bridge plate 26 provided along its edges with upturned flanges 27—27, and terminating at each end in an end flange 28 which is connected 30 with the proximate standard by means of a screw 29 entered through a bushing 30 of rubber or the like provided with a reduced neck portion 31 which projects through an aperture 32 in the flange 28 and is held in place by a washer 33 and 35 nuts 34. This arrangement provides cushioned connections between each end of the bridge plate and the proximate standard for the purpose of reducing noise and wear and more effectively imparting vibration to the standards and the platform supported thereby.

The vibratory motions are imparted by an unbalanced motor 35 which is suspended from the center of the bridge plate by a centrally disposed bracket 36 attached to the top of the motor and 45 having upwardly extending arms 37 which are directly secured to the under surface of the bridge plate by screws 38 and nuts 39. The support afforded by the bracket is supplemented by a U-shaped suspending strap 40 which embraces the motor and terminates in flanges 41 which are secured to the bridge plate by screws 42 and nuts 43.

The motor shaft 44 projects outwardly at each end, and each of the projecting end portions of 55

the shaft carries a weight 45 mounted upon a stem 46 terminating at its inner end in a head 47 which embraces the motor shaft and is held rigidly thereon by a set screw 48. Both of the 5 weights extend in the same direction, so that in conjunction they afford an unbalanced condition for the motor, with the result that as the motor shaft rotates at a rapid speed the centrifugal action of the weights will tend to produce an outward thrust which progressively travels around the orbit of the weights, thereby imparting a very rapid and intense oscillatory movement to the slightly resilient standards which support the platform. In order to cool the motor, fan blades 10 15 49 are interposed between the motor and the weight at one end of the motor shaft, and circulation of air to and around the motor is insured by the provision of apertures 50 and 51 in the side walls of the casing.

20 Power is supplied to the motor through a cable 52 entered through the bottom or base of the casing and terminating in a plug 53 which may be plugged into any electric power socket. A rheostat 54 is provided for regulating the strength 25 of the current, so that the rate of rotation of the motor and the consequent intensity of the vibration may be regulated as desired to meet the requirements of each individual case.

In use, the vibrator will be placed upon the 30 floor or other convenient support, depending upon the position to be assumed by the user, and the user will stand, sit or lie, or otherwise rest upon or against the platform, so that the rapid vibrations to which the platform is subjected will be 35 imparted to the body of the user.

Ordinarily the device will be placed upon a floor and the user will stand upright on it, and where it is desired to most effectively impart vibrations to the entire body, the user will rest upon his heels so that the vibratory effect will be 40 imparted directly through the legs and spine to all portions of the body, the intensity of the vibration being controlled by the regulation of the rheostat.

45 By suspending the motor from the bridge plate, which in turn is hung between the resilient standards upon which the platform is supported, the entire effective action of the unbalanced motor will be imparted directly to the platform, which 50 arrangement involves a highly desirable simplification in structure and in the reduction of the number of parts required and the ruggedness and durability of the structure as a whole, and by cushioning the connections in the manner described to prevent a metal to metal contact of the 55 vibrating parts, friction and wear, as well as mechanical noises, will be avoided and the durability of the structure enhanced.

I claim:

60 1. In a vibrator, the combination of a base, spaced resilient standards secured at one end to the base and being free to vibrate at their opposite ends, a rigid platform carried by the free ends of the resilient standards, a bridge member 65 secured at its opposite ends to the standards at points intermediate the platform and the points of securement of the standards to the base, and an unbalanced motor suspended from the bridge member and between the standards.

2. In a vibrator, the combination of a casing provided with a base wall, a pair of resilient standards within the casing and in spaced relation to one another and having their lower ends secured to the base wall and their upper ends 5 free to vibrate, a rigid platform mounted upon the free upper ends of the standards and elevated above and out of contact with the casing, a bridge plate extending between intermediate portions of the standards and having its ends secured thereto, and an unbalanced motor suspended from the bridge plate and between the standards.

3. In a vibrator, the combination of a casing provided with a base wall, a pair of resilient standards within the casing and in spaced relation to one another and having their lower ends secured to the base wall and their upper ends free to vibrate, a rigid platform mounted upon the free ends of the standards and elevated above and out of contact with the casing, a bridge plate 10 15 extending between the standards and having its ends secured thereto below the platform, an unbalanced motor suspended from the bridge plate, and cushioning members interposed between the ends of the bridge plate and the standards and cushioning members interposed between the free ends of the standards and the platform.

4. In a vibrator, the combination of a base, a pair of resilient standards in the form of relatively broad thin plates rigidly secured at their 30 lower ends to the base and having their upper ends free to vibrate, a platform mounted upon the upper ends of the standards, a bridge plate extending between the standards and below the platform and having its ends supported from the 35 standards, and means carried by the bridge plate and adapted to impart vibratory movements through the bridge plate to the free ends of the standards and the platform carried thereby.

5. In a vibrator, the combination of a base, a pair of resilient standards in the form of relatively broad thin plates rigidly secured at their lower ends to the base and having their upper ends free to vibrate, a platform mounted upon the upper ends of the standards, a bridge plate 40 45 extending between the standards and below the platform and having its ends supported from the standards, and motor means carried by the bridge plate and adapted to impart vibrations through the bridge plate and standards and to the platform carried thereby.

6. In a vibrator, the combination of a base, a pair of resilient standards in the form of relatively broad thin plates rigidly secured at their lower ends to the base and having their upper 55 ends free to vibrate, a platform mounted upon the upper ends of the standards, a bridge plate extending between the standards and below the platform and having its ends supported from the standards, motor means suspended from the bridge plate and adapted to impart vibrations through the bridge plate and standards and to the platform carried thereby, and cushioning means interposed between the ends of the bridge plate and the standards and cushioning means 60 65 interposed between the free ends of the standards and the platform.

JOHN G. KREINZKE.
